UNITED STATES PATENT OFFICE.

WILLIAM ALEX WALLACE, OF CHICAGO, ILLINOIS.

HAT HANGER.

Application filed January 4, 1923. Serial No. 610,629.

To all whom it may concern:

Be it known that I, WILLIAM ALEX WALLACE, a citizen of the United States, residing at Chicago, in the county of Cook and State of Illinois, have invented certain new and useful Improvements in Hat Hangers, of which the following is a specification.

My invention relates to improvements in hat hangers and has particular reference to a hat hanger that may be collapsed so as to be capable of being transported from place to place, in the pocket of the user.

An important object of my invention is to provide a hat hanger, that may be used in theatres, churches, or in fact any place where large gatherings are located, and where there are not sufficient coat racks.

Another important object of my invention is to provide a hat hanger, which may be mounted upon the back of a chair, and which will not interfere with the user of the chair, but which will be especially easy to put in place and to fold up when it has performed its use.

Another important object of my invention is to provide a hat hanger, that is exceptionally strong, durable, very simple in construction, inexpensive, and well adapted to the use for which it is designed.

Other objects and advantages of the invention will become apparent during the course of the following description.

In the drawings, wherein like numerals are employed to designate like parts through the same,

Figure 1 is a perspective view illustrating my invention in use,

Figure 2 is a perspective view illustrating my invention in a folded closed position,

Figure 3 is a front elevation of the device in a closed position,

Figure 4 is a section taken substantially on the line 4—4 of Figure 1 and looking in the direction of the arrow, and

Figure 5 is a rear elevation illustrating the device in a closed or inoperative position.

In the drawings, wherein for the purpose of illustration is shown the preferred embodiment of my invention, the numeral 6 designates the body of my hanger, and is formed from preferably two elongated parallel spaced sides, being separated by means of a transverse webbing located between the sides and made integral therewith, said webbing being located preferably intermediate the longitudinal edges of the

sides, so that the body is substantially I-shaped in cross section. The webbing extends from one end of the side of the body, approximately two-thirds of the length thereof, and terminates about one-third of the length of the side from the opposite end thereof.

A rod or arm 7, which is slightly longer than the body 6, is pivotally connected between the sides of the body directly below the terminal end of the webbing, by means of a pintle 8 mounted transversely of and between the sides of the body 6, and preferably near one of the longitudinal edges thereof. The lower end of the rod or arm 7 is provided with a padded foot 9 for purposes that will hereinafter be set forth. Pivotally connected slightly above the center of the body portion near the same longitudinal edge as the pivotal connection of the arm 7, is a pivotally connected link 10 which is provided near its other end with an elongated slot 11. The link 10 is pivotally connected by means of the pintle 12 and whereas the arm 7 is adapted to be adjacent one of the sides of the body 6, the link 10 is adapted to lie adjacent the opposite side thereof. A pin 13 which is carried by the arm 7 is adapted to be slidably engageable with the longitudinal slot 11.

A supporting arm 14 is pivotally mounted between the sides of the body by means of a shaft 15 near the upper end of the body 6, which is clearly illustrated in the drawings. The supporting arm 14 terminates in the angular extension 15, and is provided on its inner face with a suitable padding 16. The arm 14 when in an inoperative position is adapted to be shut down so as to be seated between the sides of the body 6, whereby the angular extension 15 will abut the webbing located between the sides of the body. In a like manner, the arm 7 and the link 10 are adapted to be seated when in an inoperative position between the sides of the body 6 on the opposite side of the webbing between said arms.

In use, when in an inoperative position the hat hanger is folded as illustrated in Figure 2 of the drawings, and may be carried upon the person of the user, in any pocket, and as this device may be constructed of very light material, it will not unnecessarily inconvenience the carrying thereof. When it is desired to use the hat hanger, the supporting arm 14 is swung upwardly whereby the an-

gular extension 15 which is padded, is adapted to engage the back of a seat or the like 17. The arm 7 is pulled downwardly whereby the pin 13 will slide in the elongated slot 11 to its other extremity thereof, whereby the padded end 9 will engage the back of the seat or the like 17, as shown in Figures 1 and 4 of the drawings. The padded foot 9 and the link 10 will act as a support for the 10 arm 7. A hat 18 may then be supported on the upper end of the arm 7, and as the arm 7 is disposed at an angle, it will be impossible for the hat 18 to become disengaged therefrom. When the hat hanger has served 15 its purpose, the hat may be removed and the hat hanger is then removed from the back of the seat 17, folded up and placed in the pocket of the user.

It will thus be seen, that I have devised a 20 very simple, yet efficient form of hat hanger that is capable of being folded into an inoperative position, in such a manner that it may easily be carried from place to place, and at the same time which may be easily 25 placed in an operative position affording excellent means whereby a hat or the like may be hung out of danger of being stepped upon or otherwise crushed.

It is to be understood that the form of my 30 invention herewith shown and described is to be taken as the preferred embodiment of the same, and that various changes in the shape, size and arrangement of parts may be resorted to, without departing from the 35 spirit of my invention or the scope of the subjoined claims.

Having thus described my invention, I claim:

1. A garment hanger of the class described comprising a straight rigid body, a 40 supporting arm for the body pivotally connected to one face of the body adjacent to the upper end thereof, a garment supporting arm pivotally connected intermediate its 45 ends to said body, the garment supporting

arm being adapted to protrude beyond the opposite faces of the body, the lower end of the garment supporting arm being padded, and means to hold the garment supporting arm at the desired angle. 50

2. A hat hanger of the class described comprising an elongated body portion substantially I-shaped in cross section, an arm slightly longer than said body portion pivotally connected near one end thereof, and a 55 link pivotally connected to said body portion and adapted to hold said arm at the desired angle.

3. A hat hanger of the class described comprising an elongated body portion substantially I-shaped in cross section, an arm slightly longer than said body portion pivotally connected near one longitudinal edge of 60 said body portion, near one end thereof, a link pivotally connected near the opposite 65 end of said body portion and slidably engageable with said arm, and means to support said body portion.

4. A hat hanger of the class described comprising an elongated body portion substantially I-shaped in cross section, a supporting arm pivotally connected near one longitudinal edge and near the top of said body portion, an elongated arm slightly longer than said body portion pivotally connected near the opposite end of said body portion and adjacent the opposite longitudinal edge thereof, the lower terminal of said pivoted arm being provided with a foot, a link being provided with an elongated slot, pivotally connected near the opposite end of the elongated body, and a pin carried by said arm adapted to be received within said elongated slot. 75

In testimony whereof I affix my signature 80 in presence of two witnesses.

WILLIAM ALEX WALLACE.
